[57] CLAIM

The ornamental design for a combined hobby cabinet and workbench, as shown and described.

DESCRIPTION

FIG. 1 is a perspective view of a combined hobby cabinet and workbench showing my new design;

FIG. 2 is a perspective view with the front lid removed and the top lid in open position for convenience of illustration;

FIG. 3 is a top plan view of FIG. 1;

FIG. 4 is a front elevational view;

FIG. 5 is a right side elevational view;

FIG. 6 is a rear elevational view thereof;

FIG. 7 is a left side elevational view thereof; and

FIG. 8 is a bottom plan view thereof.

FIG. 1

FIG. 2

FIG. 3
